Gary D. Johnson, 1824 Marcella St.,
Simi, Calif. 93065

Filed Nov. 10, 1966, Ser. No. 4,625

Term of patent 14 years

(Cl. D91—3)

FIGURE 1 is a front perspective view of a hose coupling protector showing my new design;

FIGURE 2 is a rear elevational view thereof;

FIGURE 3 is an end view taken from the right in FIGURE 2;

FIGURE 4 is an end view taken from the left in FIGURE 2;

FIGURE 5 is a sectional view taken on the lines 5—5 of FIGURE 2.

The fragmentary broken line representation of hosing in FIGURES 1 and 2 is for purposes of illustration only.

I claim:

The ornamental design for a hose coupling protector, substantially as shown and described.
